Specification for Design.

Patented Sept. 30, 1913.

Application filed June 30, 1913. Serial No. 776,705. Term of patent 7 years.

To all whom it may concern:

Be it known that I, CHARLES BLESCH, a citizen of the United States, residing at Newport, in the county of Campbell and State of Kentucky, have invented a new, original, and ornamental Design for Burial-Casket Handles, of which the following is a specification, reference being had to the accompanying drawing, forming part thereof.

The figure is a front elevation of a burial-

casket handle, showing my new design, one end of the handle-bar being broken away.

I claim:

The ornamental design for a burial-casket handle, as shown.

CHARLES BLESCH.
